ERNEST C. WEBSTER, OF OAKLAND, CALIFORNIA.

ELECTRIC WATER-HEATER.

1,288,774.

Specification of Letters Patent. Patented Dec. 24, 1918.

Application filed January 23, 1917. Serial No. 144,023.

To all whom it may concern:

Be it known that I, ERNEST C. WEBSTER, a citizen of the United States, residing at Oakland, in the county of Alameda and State of California, have invented new and useful Improvements in Electric Water-Heaters, of which the following is a specification.

The present invention relates to improvements in electric water heaters. Some of the objects of the invention are, in such a heater, to provide means for connecting the conducting wires to the electrodes which will absolutely prevent leakage of water around the connections; to provide good contacts with the electrode without the use of binding screws; and to provide a construction by which the heater can be easily assembled and disassembled. Further novel features of the invention will appear from the description thereof and will be particularly pointed out in the claims.

In the accompanying drawings, Figure 1 is a perspective view of my improved electric water heater; Fig. 2 is an enlarged broken vertical section thereof; Fig. 3 is a horizontal section through a controlling valve; Fig. 4 is a broken plan view of the faucet body detached; Fig. 5 is a plan view of an insulating block detached; Fig. 6 is a vertical section on the line 6—6 of Fig. 5; Fig. 7 is a side view of a cup-shaped element detached; Fig. 8 is a broken side view of a portion of a handle detached.

Referring to the drawing, the faucet body 1 has a seat for a tapering valve 2, a main inlet passage 3, vertical and horizontal branch inlet passages 4 and 5 leading to said valve seat, horizontal and vertical outlet passages 6 and 7 leading from said valve seat, a vertical discharge passage 8 surrounding a tapering nozzle 9 inserted in the outlet passage 6, said tapering nozzle 9 and discharge passage 8 communicating with a faucet 10 detachably secured to the faucet body.

At its upper end the vertical passage 7 expands (Figs. 2, 4) on opposite sides, as shown at 25, and also at first expands between said side portions 25 of the passage

but afterward is contracted by means of an overhanging wall 20, so that the water ascending in said passage abuts against said overhanging portion 20 and is deflected to the side, thereby, as will more plainly appear from the construction hereinafter disclosed, preventing the too sudden closure of the circuit between electrodes. Each side of passage 25 communicates with three vertically extending holes 11 formed in a cylindrical insulating block 12, the lower surface of which is cemented to the upper surface of the faucet body, said vertical holes terminating in the bottom of a circular groove 13 in the upper surface of said body. An arcuate discharge hole 14 leads downward through said body and communicates with the discharge passage 8, the upper portion of the hole 14 being bridged, as shown at 15.

Embedded within said insulating block are a central cup-shaped conductor 16 and an annular coaxial conductor 17 surrounding the cup-shaped conductor. The bridges 15 are for the purpose of strengthening the narrow part of the insulating block between the hole 14 and the annular conductor. The cup-shaped conductor 16 is externally roughened or corrugated, as shown at 18. Said conductors are connected to insulated copper wires 19, 21. The cup-shaped conductor is internally threaded, as shown at 24, and there is screwed thereinto the lower reduced portion 26 of a cylindrical graphite electrode 27, which has embedded in its lower portion a metallic conductor 28 having a head 29 adapted to contact with the inner surface of the cup-shaped conductor 16. The annular conductor 17 has at the bottom an inwardly extending flange, and said insulating block is formed with a deep groove above said flange, and in said groove is seated a hollow cylindrical graphite electrode 31. A spider 32 of insulating material is formed with a central plug 33 which is contained in a central cavity 34 in the top of the graphite electrode 27 while its arms engage the top of the graphite electrode 31. An inverted cup-shaped cover 36 having at its opening an outwardly extending flange

35 is held in position inclosing said electrodes by means of a sleeve 37 having a shoulder 38 pressing against a rubber washer 39 on said flange, said flange pressing against a rubber washer 41 on the margin of the upper surface of said insulating block, said margin being corrugated, as shown at 42 in Figs. 5 and 6, said sleeve 37 being screwed, as shown at 10 43, upon the top of the faucet body. The bridges 15 extend above the top of the hole 18, as shown at 40 in Fig. 2 to prevent the rubber washer 41 being moved out of place. The open end of an outer inverted-cup-shaped cover 44 is fitted tightly on the upper 15 reduced portion of said sleeve.

It will be seen that, when the valve 2 is turned so that the valve passage communicates with both passages 5 and 7, water 20 flows through the six holes 11 into the groove 13, then between the two electrodes, and out through the spider 32, then between the outer electrode and the inner cover, and then by the passages 14 and 8 to the faucet. 25 The water then forms a means for closing the circuit between the graphite electrodes, so that current flows therebetween, heating the water. When cold water is desired the valve is turned so that the valve passage 30 communicates with both passages 4 and 6.

Said tapering valve is held in place by a spring 46 around the valve stem 47, which passes through packing 48 and a nut 49. Surrounding a cylindrical reduced portion 35 51 of said stem is a bell-shaped cover 52 formed with a lug 53 and inserted in the faucet body are pins 54 adapted to engage said lug 53 to limit the movement of the valve stem, said bell-shaped cover being secured to said valve stem by means of corrugations 56 on the outer surface thereof, which can adjustably engage corrugations 57 on the adjacent surface of a handle 58, the outer portion 59 of said valve stem being 40 45 square to fit, in any one of its positions, in an octagonal or star-shaped recess 61 in the handle. Screwed into the outer end of the valve stem, securing said handle in position is a screw 62, pressing the corrugations 57 against the corrugations 56.

It is extremely important to provide a construction such that water cannot by any possible means obtain access to any metallic parts of the apparatus which are in the 55 electric circuit, for, if such access be obtained, corrosion of said metallic parts is sure to take place. This is the reason for molding the insulating material in a single block, for, by this means, there can be no leakage of water through a space intervening between two or more separate blocks of insulating material. Moreover, it is found that, in all electric water heaters 60 65 which have exposed conductors in proximity to water, there is sure to be at some time

or other a collection of moisture upon said conductors, and if these conductors are in the electric circuit there will be a leakage of current through the conductors and corrosion thereof will take place. 70

It is to insure against this result that I not only provide a double insulation of the copper wires 19, 21, as shown at 63, 64, but I form the insulating block 12 with depending conical portions 66 molded around this 75 double insulation, and I also pass over each wire and over the insulations 63, 64, therefore, a third insulating sleeve 67, the upper end of which is passed over the conical depending portion 66 of the insulating block. 80

I claim:

1. In an electric water heater, the combination of an insulating block, a central electrode supported thereby, a tubular electrode also supported thereby and surrounding said central electrode, a faucet body to which said insulating block is secured, having an inlet opening and provided with a part against which the water entering through said inlet opening can impinge, 90 and with lateral enlargements into which it can escape after such impact, said insulating block having conduits therethrough communicating at one end with said enlargements and at the other end with the 95 space between said electrodes.

2. In an electric water heater, the combination of an insulating block having an annular groove, an annular electric conductor embedded therein, an arcuate discharge 100 hole in the insulating block outside of said conductor, and bridges bridging said discharge hole.

3. In an electric water heater, the combination of a cup-shaped conductor, a non-metallic electrode the lower end of which is detachably seated in said conductor, and a metallic conductor embedded in said electrode and having a head adapted to contact with said cup-shaped conductor. 105 110

4. In an electric water heater, the combination of metallic conductors, electrodes supported by and electrically connected with said conductors, conducting wires connected to said conductors, insulating material around the respective wires, and a block of insulating material molded around said electric conductors, conducting wires and insulating material. 115

5. In an electric water heater, the combination of metallic conductors, electrodes supported by and electrically connected with said conductors, conducting wires connected to said conductors, insulating material around the respective wires, and a block of insulating material surrounding said metallic conductors and having depending portions surrounding said insulating material on the respective wires. 120 125

6. In an electric water heater, the com- 130

bination of metallic conductors, electrodes supported by and electrically connected with said conductors, conducting wires connected to said conductors, insulating material around the respective wires, a block of insulating material surrounding said metallic conductors and having depending

portions surrounding said insulating material on the respective wires, and an insulating sleeve surrounding said insulating material on the respective wires and also the lower ends of said conical depending portions.

ERNEST C. WEBSTER.
